INDEX CARD

Filed June 29, 1927

Inventor

Charles H. Cobb

Mrs. Roberts Cushman & Woodhurn,

Atty's.

UNITED STATES PATENT OFFICE.

CHARLES H. COBB, OF NEWTON, MASSACHUSETTS, ASSIGNOR TO FILING EQUIPMENT BUREAU, INCORPORATED, OF BOSTON, MASSACHUSETTS, A CORPORATION OF MASSACHUSETTS.

INDEX CARD.

Application filed June 29, 1927. Serial No. 202,215.

This invention relates to index cards for vertical filing systems and particularly to improvements in transparent label holders which are customarily applied to the upper 5 margin of guide cards used as spacing elements to separate into groups the cards or folders constituting the filing system.

It is well understood that the principal purpose of providing label holders of this 10 type is to display the visible signals or index data appearing upon the label or index slips, whereby the filing clerk may readily and expeditiously locate a particular card or file in the system, which may comprise numerous 15 trays or cabinets. It is also well known that these trays or cabinets are frequently arranged in superposed tiers extending from the floor to a height of six feet or more, so that the searcher's line of vision may be directed 20 either perpendicularly downward upon the contents of the lowermost cabinet, or horizontally toward the files of the upper cabinets. It will therefore be observed that if the signals are to be readily visible without 25 loss of time or unnecessary effort on the part of the clerk, the label holder must be so constructed and arranged that the index slip may be viewed from a position above or in front of the holder, depending upon the location 30 of the guide card with respect to the searcher's line of sight.

It is accordingly the principal object of this invention to provide a label holder so constructed that an index slip may be displayed therein, which may bear identifying letters or numerals readily visible from a point either in the same horizontal plane or in the same vertical plane as the holder. Further objects include the provision of a 35 transparent sheath providing a label-receiving pocket, having its visible portion arcuate in cross section, and an index slip carrying two sets of signals, one of which is displayed at the front of the pocket and the other at 40 the top of the pocket.

A recommended embodiment of the invention is illustrated in the accompanying drawings, in which:

Fig. 1 is a face view of an index card 50 equipped with the improved label holder;

Fig. 2 is an enlarged section on the line 2-2 of Fig. 1;

Figs. 3, 4 and 5 are plan views of a portion of a label or index slip adapted for in-

sertion in the label holder of Fig. 2, illustrating several optional dispositions of the index characters;

Fig. 6 is a perspective view of the label holder with the index slip of Fig. 3 inserted therein; and

Fig. 7 is a section similar to Fig. 2, showing a modified form of label holder.

The guide card to which the holder is applied may be made of any suitable stiff material, such as cardboard, fibre board, or 65 heavy paper, and comprises a body portion 7 and a projecting tab or tongue 8 at its upper edge. The label holder or sheath, preferably consisting of a flexible strip of transparent material such as sheet celluloid, is 70 folded over the tab 8 so as to provide a rear flap 9 and a front flap 10. The flap 10 is so formed as to provide an open ended label-receiving pocket 11, approximately semi-circular in cross section as shown in Fig. 2, 75 at the fold portion of the strip adjacent the upper edge of the tab. The curve of that portion of the pocket which is normally visible is preferably of such character that the radius of its top part is greater than that of its 80 front part, as indicated in Fig. 2. The lower portion of the flap 10 and the flap 9 may be secured to the card by a suitable adhesive or other fastening means, thus reenforcing the tab 8 and strengthening the card margin 85 against the bending stresses to which the tab and label holder are subjected by handling.

The index slip or label 12, preferably of flexible sheet material such as paper, may be inserted at either end of the pocket 11 and 90 when positioned in the holder preferably follows the curve of the inner surface of the pocket. The vertical width of the slip 12 is preferably such that when curved to fit within the pocket, the upper and lower edges of 95 the slip abut the front face of the card tab 8, and the intermediate portion is sprung outwardly against the celluloid; thus frictionally holding the slip within the pocket and preventing accidental removal.

The label may carry appropriate index characters 13, identifying the group of cards or files which are preceded by the guide card, and these characters may be so positioned upon the face of the slip that they will appear either directly in front of the window pocket 11, as indicated by the arrow 14 of Fig. 2; near the top of the pocket, as shown by

the arrow 15; or in both positions, as illustrated in Fig. 6. The label shown in Fig. 5 is suitable for position 14 (see Fig. 1); that of Fig. 4 for top position 15; and that of Fig. 3 for the duplex display of Fig. 6. It is apparent that the portion of the index slip lying below the dotted lines of Figs. 3, 4 and 5 will occupy the bottom of the pocket 11, out of usual vision.

10 Since the lowermost portion of the label holder is not normally visible, the curve of the bottom of the pocket may be of less degree than illustrated in Fig. 2, or the bottom may be substantially flat as shown in the optional 15 construction of Fig. 7. In this modification the visible region of the pocket terminates in an elongate bottom groove 16 and the invisible area 17 extends horizontally to the surface of the card. In such case the bottom 20 edge of the index slip 18 may rest in the groove 16, while the body of the slip may follow the curve of upper portion of the pocket. It is obvious, however, that a flat index 25 slip may be utilized in this form of pocket without impairing the range of clear vision provided by the arcuate pocket.

A guide card having either type of label holder above described is simple and economical to manufacture, durable in use and attractive in appearance. Either of the types 30 of labels suggested by the forms of Figs. 3, 4 and 5, or other types, may be employed interchangeably with either form of pocket to suit the requirements of the user and particularly to permit direct vision of the signal 35 whatever may be the elevation of the trays or cabinets in which the guide cards are located, or the angle of disposition of the guide card within the cabinet.

40 I claim:

1. An index card having a strip of flexible, transparent, sheet material folded over one margin, said strip comprising a rear flap and a front flap, the upper portion of the front 45 flap having a portion spaced from the front face of the card to form a label-receiving pocket, the normally visible portion of said pocket being curved forwardly and downwardly with respect to said card face, the 50 radius of the upper portion of said curve being greater than that of the lower portion thereof.

2. An index card having a strip of flexible, transparent, sheet material folded over one 55 margin, said strip comprising a rear flap and a front flap, the upper portion of the front flap having a forwardly curved portion spaced from the front face of the card to form a label-receiving pocket, and a removable 60 label fitting in said pocket, the top of the label lying edgewise against the front face of the card and the front surface of the label substantially following the curved portion of the pocket.

65 3. An index card having a strip of flexible,

transparent, sheet material folded over one margin, said strip comprising a rear flap and a front flap, and the upper portion of the front flap having a forwardly curved portion spaced from the front face of the card to form 70 an open-ended, label-receiving pocket, the rear flap and the lower portion of the front flap being secured flatwise against the respective surfaces of the card, and a removable label fitting in said pocket with its longitudinal edges abutting the front face of the card and its front surface substantially following the curved portion of said strip. 75

4. An index card having a strip of flexible, transparent, sheet material folded over one 80 margin, said strip comprising a rear flap and a front flap, and the upper portion of the front flap having a forwardly curved portion spaced from the front face of the card to form 85 an open-ended, label-receiving pocket, the rear flap and the lower portion of the front flap being secured flatwise against the respective surfaces of the card, and a removable label fitting in said pocket with its longitudinal edges abutting the front face of 90 the card and its front surface substantially following the curved portion of said strip, said label having two sets of signals spaced vertically from each other, so that one set appears near the top of the pocket and the other approximately in front of the pocket. 95

5. An index card having a projecting tab at its upper margin, and a label holder consisting of a strip of flexible, transparent sheet material folded over the margin of the tab 10 and secured upon opposite surfaces of the card, the fold of the strip including a portion spaced outwardly from the front face of the tab, constituting a label-receiving pocket open at both ends and approximately semi-circular in cross section, and a removable label fitting in said pocket with its longitudinal edges abutting the front face of the card. 10

6. An index card having a projecting tab at its upper margin, a label holder consisting 11 of a strip of flexible, transparent sheet material folded over the margin of the tab and secured upon opposite surfaces of the card, the fold of the strip including a portion spaced outwardly from the front face of the tab, constituting a label-receiving pocket open at both ends and approximately semi-circular in 11 cross section, and a removable label fitting in said pocket with its longitudinal edges abutting the front face of the card and its front surface bearing against the curved portion of said strip, said label having two sets of signals spaced vertically from each other, so that one set appears near the top of the pocket and the other approximately in front of the 1 pocket.

7. An index card having an integral projecting tab on one margin, a strip of flexible, transparent, sheet material folded over said tab, said strip comprising a rear flap and a 1

front flap, the rear flap being secured against the rear face of the tab and the upper portion of the front flap being spaced from the front face of the tab to permit the insertion of a label therebetween, said upper portion being curved forwardly of the plane of the card and downwardly from the upper edge of the tab, and a label fitting between the front face of the tab and said front flap, the label sub-

stantially following the curved portion of the 10 front flap so that signals may be displayed on the face of the label at different elevations and in different angles of sight with respect to the card.

Signed by me at Boston, Massachusetts, 15 this 6th day of June, 1927.

CHARLES H. COBB.
